UNITED STATES PATENT OFFICE.

SEBASTIÁN AGUILAR, OF PUEBLO, COLORADO.

CLIMBING DEVICE.

Application filed January 8, 1924. Serial No. 684,922.

To all whom it may concern:

Be it known that I, SEBASTIÁN AGUILAR, a citizen of Mexico, residing at Pueblo, in the county of Pueblo and State of Colorado, **5** have invented certain new and useful Improvements in Climbing Devices, of which the following is a specification.

This invention relates to a pole climbing means intended for use in connection with **10** poles carrying telegraph, telephone, or other wires, the invention having for an object the provision of a novel device of this sort which will permit of the pole being readily climbed and enable the lineman to provide **15** a secure footing for himself at any point where he desires.

For further comprehension of the invention, and of the objects and advantages **20** thereof, reference will be had to the following description and accompanying drawings, and to the appended claims in which the various novel features of the invention are more particularly set forth.

Fig. 1 of the drawings is a side view of a **25** pole showing the invention as in use thereon.

Fig. 2 is a longitudinal sectional view thereof taken on the line 2—2 of Fig. 3.

Fig. 3 is a transverse sectional view taken **30** on the line 3—3 of Fig. 2.

Fig. 4 is a side view thereof.

Fig. 5 is a plan view of the footplate **35** which is pivoted on the said slide member.

Fig. 6 is a face view of the member which is operated by the lineman to release the **40** slide member.

Fig. 7 is a side view thereof.

Fig. 8 is an enlarged fragmentary horizontal **45** sectional view taken on the line 8—8 of Fig. 1.

Fig. 9 is a fragmentary horizontal sectional view showing a slightly modified form **50** of guide member on the post.

Fig. 10 is a similar view to Fig. 4 but showing a slightly modified arrangement.

In the drawing reference numeral 10 **55** indicates an ordinary pole such as is used in carrying telegraph or telephone wires. Extending up opposite sides of this pole are channeled members such as 11, which have inturned flanges 12 on their outer sides which retain slide members therein, these members 11 being open at the bottom for insertion of the said slide members. These slide members are in the form of boxes such as 15 which fit freely in the channeled members and are provided with grooved elements 16

which engage the flanges 12. Projecting rigidly from the face of each box is a pintle 18 on which is freely mounted a footplate 19 provided with a number of straps 20 **60** whereby it may be secured to the foot of the lineman.

Mounted in each box 15 in juxtaposed position with relation to one another is a pair of rollers 23 which are fixed on trunnions 24 **65** which project through horizontal slots 25 in the sides of the box, whereby the rollers may move toward and away from one another, apertures 26 being formed in the ends of the box to permit of the rollers projecting therefrom to engage the walls of the guide 11, the surfaces of these rollers being roughened to grip the said walls of the guide.

These rollers are adapted to be forced into engagement with the walls of the guide by **70** means of a wedge shaped member 30 which is fixed at its large end to a plate 31 vertically movable in the box 15 above the rollers, the member projecting downward between the rollers. Located between the plate 31 **75** and the top of the box are the expansion springs 32 which tend to force the wedge 30 between the rollers.

Fixed to the top of the plate 31 and extending freely upward through a suitable **80** guide aperture in the top of the box 15 is a bar 33 which has its upper end outturned between the flanges 12 as at 33'. To this bar is fixed the lower end of a telescopic rod which comprises the solid lower member 35 and the **85** hollow upper member 36 which may be secured to one another in adjusted positions by the screw 37 passing through the upper member and bearing on the lower member. Fixed to the upper end of the member 36 is **90** a spindle 38 on which is mounted a roller 39 which engages freely in the guide member 12.

As will be apparent by pulling upward on the rod 35, 36, the wedge 30 is drawn back from its operative position and the rollers **95** 23 are unlocked, the lineman then raising the whole device until the foot occupies the desired new position, release of the rod causing the springs 32 to force the wedge between the rollers and so lock the latter to **100** 165 the guide 11.

To permit of the wedge 30 being rigidly locked in its operative position between the rollers I may arrange the parts as shown in Fig. 10. As there shown lower element 35' **105** of the telescopic rod is screwed at its lower end into an offset 42 from the plate 31 which

projects forwardly through a vertical slot 43 in the box 15 the plate being shown as formed with a peripheral guide flange 44. Fixed to the rod 35' above the offset 42 is a 5 collar 45 which is adapted to bear against an offset 46 from the box 15 when the rod is rotated in a direction to unscrew it from the part 12. In this arrangement the rod element 35' is formed at its upper end with 10 a number of peripheral grooves 46 to receive the screw 37. When it is desired to lock the wedge in operative position the screw 37 is slightly loosened and the rod 35' is rotated by hand until the collar 45 bears on the member 46, thus holding the 15 wedge 30 in lowered position.

The top rod element 36 may have an apertured ear 49 formed thereon to receive a hook on the end of a strap 50 attached to the belt 51 of the lineman as 20 shown in Fig. 1. In Fig. 9 the channeled guide member 11 is secured on the periphery of pole 10.

Having thus described my invention what 25 I claim as new and desire to protect by Letters Patent of the United States is as follows:

1. In combination with a pole, and a vertical guide element in said pole, a member 30 engaged with said guide element and adapted to have the foot of the user attached thereto, devices carried by said member for gripping the said guide element, a part in said member for moving said devices to 35 operative position, and a handle element for said part extending upward from the latter above the said member, and a roller on the upper end of said handle element engaging in said guide element.

2. In combination with a pole, and a vertical guide element in said pole, a member 40 engaged with said guide element and adapted to have the foot of the user attached thereto, devices carried by said member for gripping the said guide element, a part in said member for moving said devices to 45 operative position, and a handle element for said part extending upward from the latter above the said member, and a roller on the upper end of said handle element engaging in said guide element, said handle 50 element being in the form of a telescopic rod.

3. In combination with a pole, and a vertical guide element on said pole, a box 55 engaged with said guide element, a footplate carried by said box, a pair of juxtaposed rollers mounted in said box for movement into and out of engagement with the said 60 guide element, a wedge movable in said box and adapted to engage between the said

rollers, and resilient means retaining said wedge in operative position between said rollers.

4. In combination with a pole, and a vertical guide element on said pole, a box 65 engaged with said guide element, a footplate carried by said box, a pair of juxtaposed rollers mounted in said box for movement into and out of engagement with the said 70 guide element, a wedge movable in said box and adapted to engage between the said rollers, and resilient means retaining said wedge in operative position between said 75 rollers, and a handle element attached to said wedge for moving it from operative engagement with said rollers.

5. In combination with a pole, and a vertical guide element on said pole, a box 80 engaged with said guide element, a footplate carried by said box, a pair of juxtaposed rollers mounted in said box for movement into and out of engagement with the said 85 guide element, a wedge movable in said box and adapted to engage between the said rollers, and resilient means retaining said wedge in operative position between said rollers, said resilient means comprising springs bearing on said wedge.

6. In combination with a pole, and a vertical guide element on said pole, a box 90 engaged with said guide element, a footplate carried by said box, a pair of juxtaposed rollers mounted in said box for movement into and out of engagement with the said 95 guide element, a wedge movable in said box and adapted to engage between the said rollers, and resilient means for retaining said wedge in operative position between said 100 and means for locking said wedge in operative position between said rollers.

7. In combination with a pole, and a vertical guide element on said pole a box 105 engaged with said guide element, a footplate carried by said box, a pair of juxtaposed rollers mounted in said box for movement into and out of engagement with the said 110 guide element, a wedge movable in said box and adapted to engage between the said rollers, and resilient means for retaining said 115 wedge in operative position between said rollers, and a handle element attached to said wedge for moving it from operative engagement with said rollers, said handle element having a screw thread engagement with said wedge and being adapted by rotation to lock the wedge in operative position.

In testimony whereof I have affixed my signature.

SEBASTIÁN AGUILAR.
